UNITED STATES PATENT OFFICE.

NICOLAI VON KORSHENEWSKI, OF BERLIN, GERMANY, ASSIGNOR TO GESELLSCHAFT FÜR DRAHTLOSE TELEGRAPHIE M. B. H., OF BERLIN, GERMANY, A CORPORATION OF GERMANY.

ARRANGEMENT FOR MULTIPLEX DIRECTIONAL RECEIVING.

Application filed June 19, 1924, Serial No. 720,909, and in Germany June 28, 1923.

My invention relates to receiving arrangements used for receiving radio signals and has for its object to provide a multiplex directional receiving arrangement, by means of which several different wave lengths may be received simultaneously from one direction only.

A further object of the invention is to provide such an arrangement which will employ as its sole aerial means, a loop aerial appropriately grounded.

These and other objects will be apparent from the following description and claims when considered with the accompanying drawing, in which:

Fig. 1 shows a receiving arrangement in which one grounded loop aerial and two high aerials are used.

Fig. 2 shows a receiving arrangement in which only one loop aerial appropriately grounded is used.

Fig. 3 shows a modification of a detail of the arrangement shown in Fig. 2.

The known arrangements for the simultaneous directional receiving of several wave lengths by means of an aperiodic directional aerial arrangement, are such that the frame aerial effects of the different waves are aperiodically led across a circuit by means of non-reactive vacuum valve couplings to the receiving circuits tuned to the wave lengths to be received.

A simultaneous double-sided directional receiving can be attained for every desired wave length with such an arrangement. In order to attain a one-way directional effect for the receiving of the different wave lengths, the directional aerial is combined in the known way with a high aerial for each wave length. This aerial arrangement has a one-way directive receiving characteristic for each frequency to be received. The shape of the characteristic can be altered in the known way and the positions of the angles at which no signals can be received adjusted by suitably regulating the amplitudes and phases of the frame aerial effect and different high aerial effects.

Fig. 1 of the annexed drawing shows the principle of the connection of such an arrangement. A is the aerial from which the directive aerial effects are aperiodically led by means of coupling 10 and circuit K to non-reactive coupling arrangement c. From

non-reactive coupling arrangement c the directive aerial effects are led to the receiving circuits 1, 2 and 3 by means of couplings 11, 12 and 13 respectively. Receiving circuits 1, 2 and 3 are tuned to wave lengths λ_1 , λ_2 , and λ_3 by means of variable condensers 14, 60 15 and 16 respectively.

The frame aerial A is grounded and used as one high aerial A_1 . Two auxiliary high aerials A_2 and A_3 are also used. The aerial effects of the three high aerials A_1 , A_2 and A_3 are transferred to circuits K_1 , K_2 and K_3 by means of couplings 17, 18 and 19 respectively. From circuits K_1 , K_2 and K_3 these effects are transferred to the receiving circuits 1, 2 and 3 by means of couplings 70 20, 21 and 22.

High aerials A_1 , A_2 and A_3 have condensers 23, 24 and 25 for tuning to the desired frequency or adjusting the phase of the voltage induced into the receiving circuits from the high aerials.

As is well known the frame aerial effect and a high aerial effect for a particular wave length is combined in each of the receiving circuits 1, 2 and 3 to give the desired one-way directional receiving characteristic. This known arrangement guarantees a good simultaneous receiving of several different wave lengths free from disturbances, but this arrangement is very expensive, because 85 just as many high aerials are required as wave lengths to be simultaneously received.

Referring to Fig. 2, according to the present invention, all aerial effects necessary for attaining the desired receiving characteristic are supplied by one single combined high aerial and frame aerial B for all frequencies. The voltages of the different frequencies due to the high aerial effects are led from this aperiodic high aerial (or an aerial, the natural frequency of which much differs from the receiving frequencies) to the input circuits of vacuum valves R_1 , R_2 and R_3 , by means of couplings 30, 31 and 32. The plate-filament circuits of these valves 100 are connected to oscillatory circuits 33, 34 and 35 tuned to the frequencies λ_1 , λ_2 and λ_3 by means of condensers 36, 37 and 38.

It is obvious, that the intensity of currents in circuits 33, 34 and 35 is independent of the direction of the incoming waves and corresponds to the aerial effect of the high aerials tuned to these wave lengths. The

energy of these oscillatory circuits is led by means of couplings 39, 40 and 41 to the circuits H_1 , H_2 and H_3 and thence by means of couplings 42, 43 and 44 to the corresponding receiving circuits 61, 62 and 63, which are tuned to the wave lengths λ_1 , λ_2 and λ_3 .

The energy due to the frame aerial effect is led to circuit H by means of coupling 45 and thence to non-reactive vacuum tube coupling C' . From this coupling the frame aerial effect is led to receiving circuits 61, 62 and 63 by means of couplings 46, 47 and 48.

15 As in the case of the arrangement shown in Fig. 1 the high aerial effect and the frame aerial effect for each wave length is combined in the particular receiving circuit tuned for that wave length to obtain the desired one-way directional receiving characteristic.

It is not necessary to use a separate vacuum tube for each frequency, but a common vacuum tube R can be employed, the plate-filament circuit of which contains several oscillatory circuits 51, 52 and 53 tuned to the single wave lengths as shown in Fig. 3. Of course, this connection may be suitably altered. It is, for instance, possible to use 25 a common aperiodic cable for transferring the single aerial effects instead of the separate cables H_1 , H_2 and H_3 and furthermore couplings without reaction in order to prevent mutual disturbances of the single waves. 35 Besides the known means for producing phase-displacement (phase-regulators) must be present in order to be able to suitably adjust the phases of the aerial effects.

Having described my invention, what I 40 claim is:

1. In combination, a directional aerial, means associated therewith and tuned to different frequencies for producing a plurality of non-directional antenna effects, means for 45 combining the effects produced by the directional aerial and said non-directional means, said combining means having a tuning element for each of the non-directional effects whereby more than one frequency may be simultaneously received on the aerial and first mentioned means from a single direction.

2. In combination, an aperiodic directional aerial, tuned means associated therewith 55 for producing non-directional antenna effects, circuits for combining the effects pro-

duced by the aerial and said tuned means, said circuits having a tuning element for each of the non-directional effects whereby more than one frequency may be simultaneously received.

3. In combination, a single aperiodic directional antenna, aperiodic amplifying means associated therewith, means associated with said antenna for producing non-directional antenna effects, means for combining the effects produced by the antenna and the last mentioned means, said combining means having tuned amplifiers and different tuning elements for each of the non-directional effects whereby a series of different frequency signals may be received through but one direction.

4. In combination a single aperiodic directional antenna a series of aperiodic vacuum tube amplifying circuits associated therewith for producing a plurality of directional antenna effects, a series of tuned vacuum tube amplifier circuits for producing non-directional antenna effects, means comprising a plurality of receiver circuits each associated with one of said aperiodic circuits and with one of said tuned circuits whereby a series of strengthened signals of different frequencies may be received from 75 one direction.

5. In combination a grounded loop antenna, a plurality of aperiodic amplifiers associated with said loop, a receiver coupled to each of said amplifiers, a plurality of tuned amplifiers coupled to the ground connection of said loop antenna, said tuned amplifiers each being also coupled to one of said receivers whereby the signals set up in said receivers by said loop acting as a directional 90 antenna will be strengthened by signals set up in said tuned amplifiers by said loop acting as a non-directional antenna.

6. In combination a grounded loop antenna a coil in series in said loop, a series of aperiodic amplifiers coupled to said coil for directional reception, a plurality of coils in the grounded connection of the loop, a second series of amplifiers each coupled to one of the coils in the ground connection of said loop antenna for non-directional reception and a series of receivers each coupled to one amplifier of each series whereby a series of different frequency signals may be received through but one direction.

NICOLAI VON KORSHENEWSKI.
